Design No. 11,963, dated September 14, 1880.

UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A KNOB-ROSE.

SPECIFICATION forming part of Design No. 11,963, dated September 14, 1880.

Application filed June 23, 1880. Term of patent 7 years.

To all whom it may concern:

Be it known that I, GEORGE S. BARKENTIN, of New Britain, in the county of Hartford and State of Connecticut, have invented and produced a new and original Design for Knob-Rose, (Case F,) of which the following is a specification, reference being had to the accompanying wood-engraving, forming part thereof.

10 The leading feature of my design consists of a raised square plate having beveled sides, each side being paneled and ornamented with any suitable device, as shown in the engraving, in which A is the plate or rose, the sides 15 of which are beveled, as shown at B. The upper surface, C, is preferably made flat, and is countersunk so as to receive the knob-shank. The surfaces of the beveled sides are recessed, having upon each the leaf ornaments D D and 20 the semicircular ornament E in relief.

It will be seen that this form of rose may be placed upon and form a part of a rose and

escutcheon combined, as shown in the engraving, or it may be separated therefrom at the dotted lines x x and used as a knob-rose simply. 25

I claim as my invention—

1. The design of the peculiar form of rose, consisting of a raised square surface having beveled sides, substantially as shown and described. 30

2. The design of the rose A, having upon its beveled sides the leaf-ornaments D D and the semicircular ornament E, placed in relief upon a sunken panel, as shown and described. 35

3. The design of the raised square rose A, having beveled sides, in combination with the design of the escutcheon, as shown and described.

GEORGE S. BARKENTIN.

Witnesses:

CHARLES PECK,
CHARLES F. CORBIN.
